UNITED STATES PATENT OFFICE.

ALFRED J. HEINKE, OF TOWACO, NEW JERSEY, ASSIGNOR TO H. R. MALLINSON & CO. INC., OF NEW YORK, N. Y., A CORPORATION OF DELAWARE.

DESIGN FOR A TEXTILE FABRIC OR SIMILAR ARTICLE OF MANUFACTURE.

Application filed October 24, 1928. Serial No. 28,601. Term of patent 3½ years.

To all whom it may concern:

Be it known that I, ALFRED J. HEINKE, a citizen of the United States of America, residing at Two Bridges Road, Towaco, in the county of Morris and State of New Jersey, have invented a new, original, and ornamental Design for Textile Fabric or Similar Article of Manufacture, of which the following is a specification, reference being had to the accompanying drawing, forming a part thereof, and showing a face view of a piece of textile fabric embodying my design, the shading being used to indicate difference in colors and not to designate specific colors.

In the drawing, the figure is a view of a portion of fabric or the like showing the new design. A complete unit is enclosed between the broken lines A—A', B—B', C—C' and D—D', and this unit is repeated in the relation wherein the angle C'AA' coincides with angle D'EE' indefinitely throughout the fabric as shown.

I claim:

The ornamental design for a textile fabric or similar article of manufacture substantially as shown and described.

ALFRED J. HEINKE.
